DESCRIPTION

U.S. PATENT DOCUMENTS

FIG. 1 is a top and right front perspective view of a wall
mountable clock showing my new design;
FIG. 2 is a front elevational view thereof;
FIG. 3 is a left side elevational view thereof, the right side
being a mirror image; and,
FIG. 4 is a top plan view thereof, the bottom plan being a
mirror image.

The broken line showings of a dial and hands in FIGS. 1 and
2 are illustrative of environment only and form no part of the
claimed design.
